CIRCUIT CLOSER FOR FLASHLIGHTS

Orville T. Wood, Clinton, Mass., assignor to Blake Manufacturing Corporation, Clinton, Mass., a corporation of Massachusetts

Application May 28, 1942, Serial No. 445,109

18 Claims. (Cl. 200—60)

This invention relates to electric flashlights and hand lanterns of the kind in which a removable battery of dry cells is connected and disconnected at will to an incandescent lamp from which the light is reflected in a given direction.

More particularly the invention relates to a circuit closer for such flashlights.

The primary object of the present invention is to provide a circuit closer which may be readily disassembled from a flashlight so that broken parts may be replaced and the circuit closer reassembled into the flashlight.

Another object of the invention is a flashlight switch which readily adapts itself to assembly and disassembly with respect to the flashlight without the use of tools.

It is also an object of the invention to provide a flashlight in which the switch or circuit closer is positively locked in at least open circuit position to prevent accidental exhaustion of the battery when the flashlight is carried in a tool box or otherwise not in use.

Still another object of the invention is a flashlight circuit closer characterized by few parts and whereof the component parts are simple of construction and easily replaced.

The invention also seeks a flashlight to which the circuit closer of this invention may be readily adapted.

Yet another object of the invention is a circuit closer particularly adapted to a so-called insulated flashlight.

These and other objects of the invention and the means for their attainment will be more apparent from the following detailed description, taken in connection with the accompanying drawings illustrating one embodiment by which the invention may be realized, and in which:

Figure 1 is a view, in side elevation, showing a flashlight to which the present invention has been applied, parts being sectioned to show details of construction;

Figure 2 is a transverse sectional view of the circuit closer taken in the plane indicated by the line 2—2 of Figure 1, looking in the direction of the arrows and with the contact strip in open circuit position;

Figure 3 is a perspective view showing the circuit closing contact strip of this invention;

Figure 4 is a view showing a modification of the circuit closing means;

Figure 5 is a transverse sectional view taken in the plane indicated by the line 5—5 of Figure 4;

Figure 6 shows a modified form of the invention of Figure 4;

Figure 7 is a transverse sectional view of the structure shown in Figure 1 taken in the plane 5 indicated by the line 7—7 of Figure 6;

Figure 8 is a sectional view taken in the plane indicated by the line 8—8 of Figure 6;

Figure 9 is a view showing the fastening device of this invention;

10 Figure 10 is a view in side elevation of the fastening device of Figure 9;

Figure 11 is a view, in longitudinal section, showing a modification of the fastening means;

15 Figure 12 is a view, in transverse section, taken in the plane indicated by the line 12—12 of Figure 11, looking in the direction of the arrows; and

Figure 13 is a view of the slide of Figure 12 showing particularly the surface adjacent the 20 flashlight casing.

Referring first to Figure 1, the flashlight to which the present invention is illustrated as applied is a so-called insulated flashlight whereof no metal parts are exposed so that the flashlight 25 may be handled and set down among electrical equipment without danger of short circuit. As shown, the flashlight casing comprises a metallic cylindrical shell 7 threaded at its one end, as at 9, which, in the illustrated embodiment, is what 30 may be considered the bottom end of the flashlight and at its opposite or upper end increases progressively in diameter, as at 11, to a cylindrical threaded portion 13.

The threaded upper end 13 supports the rim 35 or lip 15 of the reflector 11, there being insulation 19 surrounding the lip 15 whereby the reflector is insulated from the conductive casing 11. Resting on the insulation 19 is a lens 21 of any 40 desired characteristic. Lens 21 is held in position on the threaded end 13 of the casing by a lens ring 23 screwed on to the threaded end 13.

The reflector is illustrated as of the type shown in copending application Serial Number 180,949 filed December 21, 1937, now Patent No. 2,274,178

45 issued Feb. 24, 1942. The lamp is supported within the reflector by a cup-shaped enclosure 25 which terminates in a contact 27 adapted to make electrical connection with the central terminal 29 of the battery 31, the battery 31 being 50 held against the contact 27 by a battery positioning spring 33 in the bottom cap 35. Cap 35 is removably secured on the threaded end 9 of the casing. The circuit is completed from the battery positioning spring 33 through the casing 7 55 and contact strip 81 of the circuit closer of this

invention which is described more in detail subsequently herein. The reflector 17 contacts with and conducts electric current to that lamp terminal which is not electrically connected to the battery terminal 29.

The flashlight of this invention is completely covered by insulating material. In the illustrated embodiment, the casing 7 is enclosed by a cylindrical outer casing member 39 of dielectric material, such as fiber. As shown, the lower end of this fiber covering 39 terminates at a point which permits the bottom cap 35 to be screwed on the lower end of the casing. The bottom cap is illustrated as covered by a removable insulating cap 41, preferably of rubber, having a flexible lip 43 adapted to overlie the lower end of the fiber casing 39.

The upper end portion of the flashlight is enclosed within a member of insulating material, preferably rubber, consisting of a cylindrical portion 45 having the inturned lip 47 which overlies the lens ring 23 and a constricted somewhat thinner and more flexible rubber portion 49 which terminates in a flexible annular lip 51 which overlies the upper end of the fiber housing 39 so that, by means of these three elements 39, 41 and 45-51 of insulating material, all the metallic parts of the flashlight are completely enclosed or covered by dielectric material.

The circuit closer of this invention is particularly applicable to a flashlight of the character just described although by no means confined in its use thereto. An opening 53, preferably rectangular, is formed in the dielectric outer casing 39. This opening is preferably of its longest dimension in the longitudinal direction of the casing. The metallic inner casing 7 is formed with an opening 55 substantially registering with the opening 53 and having an outwardly deflected tongue or lip 57 integral therewith which extends upwardly and forwardly in the opening 53 to serve as a stop for the circuit closer in this retracted position. This lip 57 is an edge or surface angularly related to the contact strip 81. The rear end of the slot 55 in the brass case 7 is thus deflected upwardly for two purposes. The first purpose is to help retain the fiber tube and the brass tube piercings 53 and 55 in register. The second purpose is to provide a sloping guide surface against which the rearmost end 91 of the contact strip will cam or slide out of the opening 53 during the time when the strip is inserted into the slide.

Slidable on the outer surface of the dielectric casing 39 is the slide or thumb piece 61 which may conveniently be rectangular in plan, and of transverse and longitudinal dimensions to materially overlie the surface of the casing 39 on all sides of the opening 53 in all positions of the slide. The surface of the slide 61 proximate the dielectric casing 39 is formed of a curvature whose radius is substantially that of the radius of the outer surface of the dielectric casing 39, as shown at 63 in Figure 2.

The upper surface or exposed surface of the slide 61 may be of any convenient configuration to permit engagement by the thumb, say, of the hand holding the flashlight, to permit the manipulation of the circuit closer. Thus, in the illustrated embodiment, forwardly of the midpoint of the slide 61, the slide is formed with an elevated portion 65 and is then of progressively changing thickness in a vertical dimension to a low point 67 from which point the slide is of increased thickness, as at 69, but of lesser thick-

ness than the portion indicated at 65 and is corrugated or otherwise roughened, as at 71, to provide a surface which will be conveniently engaged by the thumb of the manipulator without slipping.

At a thicker portion of the slide and on the axis thereof, the inner surface 63 is formed with a rectangular recess 73 which receives a sleeve 75 of rectangular cross-section secured in position on the slide by means, say, of a screw 77. In order to permit access to the head of the screw 77, the inner face of the sleeve 75 is slotted, as at 79, and in register with the aperture through which the screw passes. The slot is of increased diameter sufficient to permit the passage of the head of screw 77 as shown in Figure 2.

Carried with the slide 61 within the casing member 7 is a reciprocating contact strip indicated generally at 81 and shown in perspective in Figure 3. At this forward or upper end, the contact strip is deflected somewhat, as at 83, as a contact surface to engage and make electrical connection with, say, the reflector 17 of the flashlight. Intermediate its contact portion 83 and the slide, the contact member is formed with a longitudinal rib 85 for strength and to space slightly the contact member from the inner conductive casing 7.

That portion of the contact strip 81 proximate the slide 61 is offset inwardly, as at 87, and is formed with inwardly deflected tongues 89 and 90 which are shown in Figure 3 as four in number, two along each edge of the strip and directed toward one another to form stops, it being observed that the spacing of the tongues 89 and 90 are such as to snugly receive between them the bottom 78 of the sleeve 75 on the slide when the circuit closer 81 is disposed in its normal position within the sleeve 75.

Rearwardly of the opening 55, the inner conductive casing 7 is formed with an inwardly offset portion or boss 59 having angularly related sides or ends 58, 60, that is, sides which slope in the direction of the axis of the casing 7 and of a dimension, in the circumferential direction of the inner casing 7, conveniently less than the circumferential dimension of the opening 55. At its rear end, the circuit closer 81 is provided with a radially directed bent-up end portion or lug 91 which normally bears on the inner surface of the conductive casing 7 to retain the contact member 81 in spaced relation to the inner casing 7. Thus, the lug 91 and the offset 87 together with the rib 85, if present, serve to hold the sliding contact 81 against the inner side of the sleeve 75 so that it cannot work loose as the slide is manipulated. When the lug 91 is at the rearmost portion of the boss 59, it serves, to some extent, as a retaining latch for the open circuit position of the switch contact strip. When the switch contact strip is advanced to the closed circuit position, the lug 91 will then be positioned forwardly of the boss 59 so as to releasably retain the switch contact strip in closed circuit position.

Additional latching means are provided for the contact in open circuit position to prevent the inadvertent closing of the circuit and exhaustion of the battery when the flashlight is not in use, say, when carried in the pocket or a tool box. As shown, a strip-like latching member 93 of suitable resilient material is secured at one end within the recess 73 and is formed with successively inwardly offset portions 97 and 99, the off-

set portion 99 being formed with a radially extending outwardly bent latching end 101 which is so positioned as to be engaged by an inwardly deflected stop 103 struck inwardly from the casing member 7. To actuate the latch 101 in order to release the slide for movement to closed circuit position, the portion 67 of the slide is formed with a radially extending passage. Conveniently this passage is of one dimension at its outer end, as at 105, and of a greater dimension, as at 107, at its inner end. Thus a plunger 109, 111 is disposed in the passage. It is of a length somewhat greater than the thickness of the slide at this point so that it can be normally held with its end of smaller diameter outwardly of the slide for convenient engagement by the finger. The head 111 of the plunger is disposed in the passage portion of increased diameter and is normally urged upwardly into engagement with the shoulder by the engagement therewith of the portion 97 of the resilient latch member 93. To release the latch, in order to permit the slide and contact strip to be moved to circuit closed position, it is merely necessary to depress the plunger with that finger of the same hand that manipulates the slide.

To retain the slide against lateral movement and to form a guideway or channel for the contact 81 to move in, semi-circular bosses 113 are struck inwardly in the conductive casing 7 two on each side of the path of the slide 81 so that the opposed straight sides of these bosses form, in effect, the walls of a groove within which the contact 81 reciprocates. These bosses also space the battery 31 from the contact member 81.

The structure just described permits the circuit closer to be readily disassembled. To remove the switch in the flashlight illustrated, the flexible rubber hood 51 is first rolled back away from the lens ring 23 and the lens ring which carries the lens and reflector assembly is then unscrewed from the flashlight casing. Obviously, if no insulatory material such as the hood 45, 49, 51 is present, it would merely suffice to remove the lens ring and withdraw the reflector and lamp socket to permit access to the interior of the casing. The batteries, if present, would then be removed so as to permit the insertion of a finger.

For removal, the slide 61 is moved to circuit closed position, shown in Figure 1. The finger is then inserted and pressure exerted against the inner surface of the offset portion 87 say, between the lug 91 and the adjacent pair of tongues 90. Pressure against the tensioned contact strip at this point moves the offset portion as a whole inwardly within the sleeve 75 and releases engagement of the tongues 90 with respect to the wall 78 of the sleeve permitting the contact member 81 to be slid forwardly by the frictional engagement of the finger which exerts the pressure and removes the strip out the open end of the casing. The slide 61 is then free to be lifted off the casing, carrying with it the sleeve 75.

Assembly of the circuit closer is accomplished by reverse of these steps. The slide is first placed in position with the sleeve entering the openings 53 and 55, the sleeve 75 being in the rearmost end of the openings, i. e., the end toward the bottom cap. The contact strip 81 is then inserted with the deflected end 91 directed toward the casing 7 and pushed through the sleeve 75 until the tongues 89 and 90 snap into place on opposite

sides of the sleeve 75 when the switch is assembled and ready for operation.

Modifications of the means to attach the sleeve 75 to the slide 61 are illustrated in Figures 4 through 8.

In the modification of Figures 4 and 5, the slide 61 and its associated parts are identical with that heretofore described except for the fact that the slide is formed with a cylindrical lug 115 and the 10 apertures in the sleeve 75 and latching member 93 are formed with apertures to fit over the lug 115. Both sleeve and latching member are retained in position on the lug by a fastening device illustrated in Figures 9 and 10 as comprising a piece of resilient sheet material 117 such as 15 spring steel, which may be circular or rectangular or polygonal in outline and is formed with a rectangular opening 119 stamped therefrom and is slotted along opposite sides, as at 121, to define two free wings 123. When this member 117 is forced on the lug 115 and against the sleeve 75, the wings 123 engage the lug, say, by biting into the lug slightly, as shown, and urge the sleeve 75 and latching member 93 tightly against the slide and hold it in position. This is an expedient way of assembly and securely holds the parts in proper position.

In lieu of a separate fastening device 117, the sleeve and the latching member may be formed as an integral member, as shown in Figures 6 30 through 8. Here the latching member 127 is formed in its innermost side 129 with the engaging means of Figures 4 and 5.

The innermost side of the sleeve 75 is formed 35 with the rectangular aperture 119 (Figure 8) and slotted as at 121 so that when forced on the lug 115, the forked edges of the wings 123 will bite into the lug, as in Figure 7, and hold the sleeve tightly in position. The end of the latching member 127 is widened transversely, as at 131, and the sides 131 are bent downwardly, as at 133, and inwardly to provide a sleeve similar in function to the sleeve 75 but providing a combined latching member and contact strip carrying 40 sleeve which has incorporated therein the fastening means of this invention.

In lieu of fastening means on the principle of Figures 9 and 10, the somewhat different fastening device of Figures 11, 12 and 13 may be 45 adopted. Here the slide 135 is formed with a rectangular recess 137 and the bottom of this recess is formed with a narrower recess 139 and at the center of the recess 139 the slide is formed with a cylindrical recess 141 formed with a keyway or slot 143. The apertured end 91 of the latching member 93 of the Figure 4 modification is fitted in the recess 139 and positioned thereagainst is a sleeve 145 substantially the same as the sleeve 75 but formed with an outwardly offset portion 147 which fits within the recessed portion 137 of the slide. A cylindrical plug 149 having a head 151 passes through the apertures in the latching member and the sleeve and enters the hole 141. Adhesive 154 fills the space between the slide portions and the portions of the latch and sleeve and also enters the key-way to securely hold the parts in position.

It will be recognized that while the circuit closer of this invention is particularly applicable to an insulated flashlight, that it is equally applicable in any situation where a circuit is to be closed by a sliding contact member and no limitation is intended by the phraseology of the foregoing description, or illustrations in the accom-

panying drawings, except as indicated in the appended claims.

What is claimed is:

1. In a flashlight, circuit closing means capable of being dismantled without the use of tools comprising the combination with an open ended casing formed with an opening intermediate its ends, a slide disposed wholly on the outer surface of the casing and movable over the opening, a tubular sleeve, disposed in the opening and comprising an outer side secured to the slide, side walls extending through the opening and an inner side within the casing in radially spaced relation to the slide, a resilient contact strip within the sleeve and supported on the inner side of the sleeve and formed remote from one end of the sleeve with an outwardly offset portion in spaced relation to the sleeve and engaging the casing and also formed remote from the opposite end of the sleeve and spaced therefrom with an offset portion engaging the casing to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with latching means, and a resilient latch carried by the slide and engaging the latching means in open circuit position of the strip.

2. In a flashlight, circuit closing means capable of being dismantled without the use of tools comprising the combination with an open ended casing formed with an opening intermediate its ends, a slide disposed wholly on the outer surface of the casing and movable over the opening, a tubular sleeve disposed in the opening and comprising an outer side secured to the slide, side walls extending through the opening and an inner side within the casing in radially spaced relation to the slide, a resilient contact strip within the sleeve and supported on the inner side of the sleeve and formed remote from one end of the sleeve with an outwardly offset portion in spaced relation to the sleeve and engaging the casing and also formed remote from the opposite end of the sleeve and spaced therefrom with an offset portion engaging the casing to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with latching means, a resilient latch carried by the slide and engaging the latching means in open circuit position of the strip and means to depress the latch to release it from the latching means and permit the slide and strip to be moved to closed circuit position.

3. In a flashlight, circuit closing means capable of being dismantled without the use of tools comprising the combination with an open ended casing formed with an opening intermediate its ends, a slide disposed wholly on the outer surface of the casing and movable over the opening, a tubular sleeve disposed in the opening and comprising an outer side secured to the slide, side walls extending through the opening and an inner side within the casing in radially spaced

relation to the slide, a resilient contact strip within the sleeve and supported on the inner side of the sleeve and formed remote from one end of the sleeve with an outwardly offset portion in spaced relation to the sleeve and engaging the casing and also formed remote from the opposite end of the sleeve and spaced therefrom with an offset portion engaging the casing to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with latching means, a resilient latch carried by the slide and engaging the latching means in open circuit position of the strip and a plunger movable in the slide to depress the latch to release it from the latching means and permit the slide and strip to be moved to closed circuit position.

4. In a flashlight, circuit closing means capable of being dismantled without the use of tools comprising the combination with an open ended casing formed with an opening intermediate its ends, a slide disposed wholly on the outer surface of the casing and movable over the opening, a tubular sleeve disposed in the opening and comprising an outer side secured to the slide, side walls extending through the opening and an inner side within the casing in radially spaced relation to the slide, a resilient contact strip within the sleeve and supported on the inner side of the sleeve and formed remote from one end of the sleeve with an outwardly offset portion in spaced relation to the sleeve and engaging the casing and also formed remote from the opposite end of the sleeve and spaced therefrom with an offset portion engaging the casing to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with latching means, a resilient latch carried by the slide and engaging the latching means in open circuit position of the strip and a plunger movable in the slide and normally elevated above the slide by the latch to depress the latch to release it from the latching means and permit the slide and strip to be moved to closed circuit position.

5. In a flashlight, circuit closing means capable of being dismantled without the use of tools comprising the combination with an open ended casing formed with an opening intermediate its ends, a slide disposed wholly on the outer surface of the casing and movable over the opening, a tubular sleeve disposed in the opening and comprising an outer side secured to the slide, side walls extending through the opening and an inner side within the casing in radially spaced relation to the slide, a resilient contact strip within the sleeve and supported on the inner side of the sleeve and formed remote from one end of the sleeve with an outwardly offset portion in spaced relation to the sleeve and engaging the casing and also formed remote from the opposite end of the

sleeve and spaced therefrom with an offset portion engaging the casing to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with latching means, a resilient strip one end of which is secured within the sleeve to the slide and having an inwardly offset first portion, a further inwardly offset second portion and an outwardly bent end engaging the latching means in open circuit position of the slide, and a plunger in the slide supported with an end above the slide by the first offset portion of the latch.

6. In a flashlight, circuit closing means capable of being dismantled without the use of tools comprising the combination with an open ended casing formed with an opening intermediate its ends, a slide on the outer surface of the casing and movable over the opening, a tubular sleeve disposed in the opening and comprising an outer side secured to the slide, side walls extending through the opening and an inner side within the casing in radially spaced relation to the slide, a resilient contact strip within the sleeve and supported on the inner side of the sleeve and formed remote from the respective ends of the sleeve with outwardly offset portions in spaced relation to the sleeve and engaging the casing to thereby place the intermediate inwardly offset portion of the strip under tension in spaced relation to the casing and in position in the sleeve whereby said strip may be disengaged from the sleeve by a finger inserted through the open end of the casing and depressing the intermediate portion of the strip outwardly toward the casing and out of engagement with the sleeve, of latching means carried by the casing, and a resilient latch carried by the slide and engaging the latching means in open circuit position of the strip.

7. In a flashlight, circuit closing means capable of being dismantled without the use of tools comprising the combination with an open ended casing formed with an opening intermediate its ends, a slide on the outer surface of the casing, and movable over the opening, a tubular sleeve disposed in the opening and comprising an outer side secured to the slide, side walls extending through the opening and an inner side within the casing in radially spaced relation to the slide, a resilient contact strip within the sleeve and supported on the inner side of the sleeve and formed remote from the respective ends of the sleeve with outwardly offset portions in spaced relation to the sleeve and engaging the casing to thereby place the intermediate inwardly offset portion of the strip under tension in spaced relation to the casing and in position in the sleeve whereby said strip may be disengaged from the sleeve by a finger inserted through the open end of the casing and depressing the intermediate portion of the strip outwardly toward the casing and out of engagement with the sleeve, said casing being provided with latching means comprising an inwardly and rearwardly struck portion, and a resilient latch carried by the slide and engaging the latching means in open circuit position of the strip.

8. In a flashlight, circuit closing means ca-

5 pable of being dismantled without the use of tools comprising the combination with an open ended casing formed with an opening intermediate its ends, a slide disposed wholly on the
10 outer surface of the casing and movable over the opening, a tubular sleeve disposed in the opening and comprising an apertured outer side, side walls extending through the opening and an inner side within the casing in radially spaced relation to the slide, a resilient contact strip within the sleeve and supported on the inner side of the sleeve and formed remote from the respective ends of the sleeve with outwardly offset portions in spaced relation to the sleeve and engaging the
15 casing to thereby place the intermediate inwardly offset portion of the strip under tension in spaced relation to the casing and in position in the sleeve whereby said strip may be disengaged from the sleeve by a finger inserted through the open end
20 of the casing and depressing the intermediate portion of the strip outwardly toward the casing and out of engagement with the sleeve, of a radially extending lug carried by the sleeve and extending through the opening and extending
25 through the aperture in the slide and fastening means engaging the lug to retain the sleeve on the slide.

9. In a flashlight, circuit closing means capable of being dismantled without the use of tools comprising the combination with an open ended casing formed with an opening intermediate its ends, a slide disposed wholly on the outer surface of the casing and movable over the opening, a tubular sleeve disposed in the
30 opening and comprising an apertured outer side, side walls extending through the opening and an inner side within the casing in radially spaced relation to the slide, a resilient contact strip within the sleeve and supported on the inner side
35 of the sleeve and formed remote from the respective ends of the sleeve with outwardly offset portions in spaced relation to the sleeve and engaging the casing to thereby place the intermediate inwardly offset portion of the strip under
40 tension in spaced relation to the casing and in position in the sleeve whereby said strip may be disengaged from the sleeve by a finger inserted through the open end of the casing and depressing the intermediate portion of the strip outwardly toward the casing and out of engagement with the sleeve, of a radially extending lug carried by the slide and extending through the opening and the aperture in the sleeve and fastening means comprising a plate having opposing wings engaging
45 the lug to retain the sleeve on the slide.

50 55

10. In a flashlight, circuit closing means capable of being dismantled without the use of tools comprising, in combination, an open ended casing formed with an opening intermediate its 60 ends, a slide disposed wholly on the outer surface of the casing and movable over the opening, a tubular sleeve disposed in the opening and comprising an apertured outer side, side walls extending through the opening and an inner side 65 within the casing in radially spaced relation to the slide, a resilient contact strip within the sleeve and supported on the inner side of the sleeve and formed remote from the respective ends of the sleeve with outwardly offset portions in spaced 70 relation to the sleeve and engaging the casing to thereby place the intermediate inwardly offset portion of the strip under tension in spaced relation to the casing and in position in the sleeve whereby said strip may be disengaged from the 75 sleeve by a finger inserted through the open end

of the casing and depressing the intermediate portion of the strip outwardly toward the casing and out of engagement with the sleeve, and an apertured resilient latch, of a radially extending lug carried by the slide and extending through the opening and the apertures in the sleeve and latch, and fastening means engaging the lug to retain the sleeve and latch on the slide.

11. In a flashlight, circuit closing means capable of being dismantled without the use of tools comprising, in combination, an open ended casing formed with an opening intermediate its ends, a slide disposed wholly on the outer surface of the casing and movable over the opening, a tubular sleeve disposed in the opening and comprising an apertured outer side, side walls extending through the opening and an inner side within the casing in radially spaced relation to the slide, a resilient contact strip within the sleeve and supported on the inner side of the sleeve and formed remote from the respective ends of the sleeve with outwardly offset portions in spaced relation to the sleeve and engaging the casing to thereby place the intermediate inwardly offset portion of the strip under tension in spaced relation to the casing and in position in the sleeve whereby said strip may be disengaged from the sleeve by a finger inserted through the open end of the casing and depressing the intermediate portion of the strip outwardly toward the casing and out of engagement with the sleeve, and an apertured resilient latch, of a radially extending lug carried by the sleeve and extending through the opening and the apertures in the sleeve and latch, and fastening means comprising a plate having opposing wings engaging the lug to retain the sleeve and latch on the slide.

12. In a flashlight, circuit closing means capable of being dismantled without the use of tools comprising, in combination, an open ended casing formed with an opening intermediate its ends, a slide disposed wholly on the outer surface of the casing and movable over the opening, a radial lug carried by the slide, a latch member having a tubular sleeve disposed in the opening and comprising an outer side formed with fastening means engaging the lug, side walls extending through the opening and an inner side within the casing in radially spaced relation to the slide, a resilient contact strip within the sleeve and supported on the inner side of the sleeve and formed remote from the respective ends of the sleeve with outwardly offset portions in spaced relation to the sleeve and engaging the casing to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with coacting latching means.

13. In a flashlight, circuit closing means capable of being dismantled without the use of tools comprising, in combination, an open ended casing formed with an opening intermediate its ends, a slide disposed wholly on the outer surface of the casing and movable over the opening, said slide being formed with a recessed portion and a cylindrical recess, a tubular sleeve substantially rectangular in cross-section, disposed in the opening and comprising an apertured outer side

disposed in the recess in the slide, side walls extending through the opening and an inner side within the casing in radially spaced relation to the slide, a resilient contact strip within the sleeve and supported on the inner side of the sleeve and formed remote from the respective ends of the sleeve with outwardly offset portions engaging the casing and also formed to thereby place the intermediate inwardly offset portion of the strip under tension in spaced relation to the casing in position in the sleeve whereby said strip may be disengaged from the sleeve by a finger inserted through the open end of the casing and depressing the intermediate portion of the strip outwardly toward the casing and out of engagement with the sleeve, said casing being provided with latching means, an apertured resilient latch disposed in the recess in the slide, a pin passing through the apertures and entering the cylindrical recess in the slide and adhesive securing the pin in the cylindrical recess.

14. In a flashlight, circuit closing means capable of being dismantled without the use of tools comprising, in combination, an open ended casing formed with an opening intermediate its ends, a slide disposed wholly on the outer surface of the casing and movable over the opening, said slide being formed with a recessed portion and a cylindrical recess, a tubular sleeve substantially rectangular in cross-section, disposed in the opening and comprising an apertured outer side disposed in the recess in the slide, side walls extending through the opening and an inner side within the casing in radially spaced relation to the slide, a resilient contact strip within the sleeve and supported on the inner side of the sleeve and formed remote from the respective ends of the sleeve with outwardly offset portions engaging the casing and also formed to thereby place the intermediate inwardly offset portion of the strip under tension in spaced relation to the slide in position in the sleeve whereby said strip may be disengaged from the sleeve by a finger inserted through the open end of the casing and depressing the intermediate portion of the strip outwardly toward the casing and out of engagement with the sleeve, said casing being provided with latching means, an apertured resilient latch disposed in the recess in the slide, a pin passing through the apertures and entering the cylindrical recess in the slide and adhesive securing the pin in the cylindrical recess and the sleeve in the recess.

15. In a flashlight, circuit closing means comprising the combination with a casing formed with an opening, a slide having a radial lug and movable over the opening, a sleeve formed with an aperture received on the lug, a resilient latch formed with an aperture receiving the lug and fastening means engaging the lug to retain the sleeve and latch in position on the slide, said slide being also formed with a radial aperture spaced from the lug and a plunger in the aperture operatively engaging the resilient latch.

16. In a flashlight, circuit closing means comprising the combination with a casing formed with an opening, a slide having a radial lug and movable over the opening, a sleeve formed with an aperture receiving the lug, latching means formed with an opening receiving the lug and a plate formed with opposed notched wings engaging the lug to secure the sleeve and latching means to the slide, said slide being also formed with a radial aperture spaced from the lug and

a plunger in the aperture operatively engaging the resilient latch.

17. In a flashlight, circuit closing means comprising the combination with a casing formed with an opening, a slide having a lug movable over the opening, a latching member formed with a sleeve, said sleeve being formed with oppositely disposed notched wings engaging the lug to retain the latching member on the slide.

18. In a flashlight, circuit closing means comprising the combination with a casing formed with an opening, a slide formed with a keyhole recess and movable over the opening, a sleeve formed with an aperture disposed in register with the keyhole recess, a pin passing through the aperture and entering the recess and an adhesive securing the pin in the recess.
